BRUSH HANDLE AND CONNECTING MEANS
THEREFOR

Robert S. Eisner, Red Bank, N. J., and Daniel Schoenholz, Flushing, N. Y., assignors, by direct and mesne assignments, to Hanlon & Goodman Co., Belleville, N. J., a corporation of New York

Application October 14, 1948, Serial No. 54,452

15 Claims. (Cl. 15—128)

1 This application is a continuation-in-part of our copending application Serial No. 751,538, filed May 31, 1947, now Patent No. 2,454,553, dated November 23, 1948. This invention relates to brushes for applying coating materials, for cleaning, etc., and particularly to handles for such brushes and to means for detachably securing the brush handle to the brush head or base, a part of which detachable securing means is carried by the handle. While the handle and the detachable connecting or securing means of the invention are particularly adapted for use in fountain, liquid-applying brushes of the general type disclosed and claimed in our aforesaid application, they also are adapted for use with the more common form of liquid-applying brushes, as well as with brushes for cleaning, scrubbing and other purposes.

It frequently is desirable to have the handle of a brush detachably connectable to the brush head or base, so that the handle may be manufactured or produced separately from the brush proper, and the two parts then connected; thus, a worn brush may be disconnected from the handle and replaced by a new one. Also, in fountain, liquid-applying brushes, it is desirable that the handle be disconnectable from the brush head or base in order to permit better cleaning of the passages in the brush head and handle through which the liquid passes.

In accordance with the present invention a new form of brush handle is provided whereby it may be made separately from the other parts of the brush and so detachably connected to the brush head that a firm, rigid connection is made between the two, so that in use of the brush there will be no relative movement between them which would interfere with the normal use of the brush or prevent the user from doing a first-class workman-like job. The connection also is one which is of simple construction and requires only a few relatively inexpensive parts, and which will neither be in the way of the user's hands, nor will present extensions or obstructions which will prevent normal handling and use of the brush.

More specifically, the brush handle has the end thereof which bears against the brush head bifurcated to provide a central space within which cooperating, separable connecting means carried by the head of the brush and the handle, respectively, are positioned. Thus, the cooperating, separable connecting means may be caused to lie in longitudinal alignment with the portion of the handle which normally is grasped when the brush is being used, so that they will not in anywise

2 interfere with the normal grasping of the brush handle, nor with the use of the brush. The connecting means are such that the distal ends of the spaced inner end portions of the handle may be brought and held into firm, rigid contact with the brush head. Interlocking means between the brush head and the spaced inner ends of the handle are provided, to prevent relative rotation between the handle and the brush head.

10 When the cooperating, separable connecting means of the invention are to be used to connect the handle to the brush head of a fountain, liquid-applying brush, they are so formed that the liquid to be supplied to the brush may pass through them to distributing passages in, or carried by the head or base of the brush.

The invention will be further described in connection with the accompanying drawings, but it is to be understood that such further description is by way of exemplification and the invention is not limited thereby.

In the drawings:

Fig. 1 is a longitudinal sectional view on line 1—1 of Fig. 2 through a paint brush of the fountain, liquid-applying type embodying one form of the new handle and detachable connecting means;

Fig. 2 is a sectional view on line 2—2 of Fig. 1;

Fig. 3 is a longitudinal sectional view on line 3—3 of Fig. 4, of a modified form of the new handle and detachable connecting means;

Fig. 4 is an enlarged sectional view on line 4—4 of Fig. 3; and

Fig. 5 is a plan view of the brush head detached from the handle.

Referring first to the form of detachable connecting means shown in Figs. 1 and 2, it will be seen that they are shown in conjunction with a fountain, liquid-applying brush of the wide, flat type, such as may be used for painting flat surfaces such as walls, ceilings or the like. The brush there shown includes a head 10 of wood or other suitable material having a passage 11 extending lengthwise thereof, that is, transversely 40 of the brush. The passage has an inlet 12 for liquid extending through one wall of the head, and two outlets 13 and 13' leading from the ends of the passage 11 through the wall of the head opposite that through which the inlet 12 extends.

45 A main body 14 of long bristles of nylon, or the like, has one end thereof embedded in or mounted on the wall of the base through which the outlets open.

Flexible conduits 15 and 16 of synthetic rubber or other oil-resistant plastic, are connected

to the head 10 at the outlets 13 and 13' in any suitable manner. The outer ends of the flexible conduits 15 and 16 are attached to a thin, flat chamber or manifold 17 embedded in the body of the bristles 14, inwardly from its outer or distal end at about the line along which the bristles are flexed when the brush is used in a normal manner. The chamber 17 is provided with a lengthwise passage 18 from which a plurality of small orifices 19, of about one millimeter in diameter, extend outwardly and through the wall facing the free end of the bristles. Paint or other coating material may be supplied under pressure to the passage 11 in the head and flow through the tubes 15 and 16 to the passage 18 in the chamber and then through the small orifices 19. A thin, relatively short body of bristles 20 has one end thereof embedded in or are mounted on the outer wall of the chamber 17 around the orifices 19. The body of bristles 20 serve as a distributing means and fill the cavity among the long bristles that otherwise would be caused by the presence of the chamber 17 and by the tendency of the long bristles to stick together when wet. The thin body of bristles 20 and the outer ends of the bristles of the main body 14 together constitute the liquid-applying means of the brush.

The handle 21 of the brush is formed with a passage 22 for liquid to be supplied to the bristles of the brush. The inner end of the handle is bifurcated to form head-engaging portions 23 and 24 which are spread apart to form a space 25 between the head and the handle and in longitudinal alignment with the main portion of the handle. The inner end of the handle is provided with a coupling nipple 26, which is threaded into the end thereof between the spaced head-engaging portions 23 and 24, and has a passage 27 aligned with the passage 22. The outer end of the inlet 12 through the brush head is enlarged to receive the distal end of the coupling nipple and the base has an externally threaded flange 27' around the inlet opening.

The spaced portions 23 and 24 of the handle are firmly and rigidly held against the brush head by a collar or coupling nut 28 which is mounted to encircle the coupling nipple 26 and is threaded onto flange 27'. When the coupling nut is secured tightly onto the flange, it acts against a circumferential shoulder on the coupling nipple to force the latter against a seat in the brush head. Preferably a gasket 29 is interposed between the collar and the shoulder on the coupling nipple to prevent leakage of liquid passing through the handle into the brush head. As the cooperating, separable fastening means are located in the space between the head-engaging portions 23 and 24 of the handle, access to the coupling nut 28 in order to connect or disconnect the handle readily is obtainable at the sides of the handle, as will clearly be seen in Fig. 2.

Pins 30 extending from the head-engaging faces of the spaced portions 23 and 24 of the handle are received in aligned openings in the head, and properly align the handle of the brush head and prevent relative rotation between the handle and the brush head which would give an insecure grip and might interfere with the paint or other coating material being applied in a first-class, workmanlike manner.

The handle is formed at its free end with a threaded section 31, by which a length of tubing 32 may be connected to the handle. The tub-

ing leads into a reservoir in which the coating fluid is maintained under pressure.

The flow of fluid from the reservoir through the handle of the brush is controlled by a valve mounted in a passage 33 through the handle. The valve includes a body 34 and a stem 35 which extends through the body and has a valve head 36 which seats against a valve seat formed in the body to cut off flow through passage 37 to the body. The stem has a button 38 at its outer end, and a spring 39 encircling the stem acts on the button to hold the valve normally closed. The valve body 34 is held in passage 33 between a pair of discs 40 and 41 threaded into the passage.

The form of brush shown in Figs. 3, 4 and 5 is of the same general type as the brush shown in Figs. 1 and 2 and comprises a head or base of wood or other suitable material having a main body of bristles 42 mounted at one end on a face thereof. The opposite face or side of the brush head has a recess 43 formed therein for receiving bifurcated end portions 44 and 44' of a handle 45.

An elongated inner feed block 46 is positioned within and extends longitudinally of the main body of bristles against the face of the brush head opposite that from which the handle extends. The feed block 46 has a passage 47 extending lengthwise thereof through which a liquid to be applied by the brush may pass to outlets communicating with the inner ends of flexible conduits 48 and 48'. The outer ends of the flexible conduits connect with the opposite ends of an outer feed block 49. The outer feed block has a lengthwise passage 50 through which coating liquid may flow to a plurality of small orifices 51 in the face of the feed block facing the ends of the bristles. The orifices 51 are surrounded by a second, or auxiliary thin body of bristles 52 which receive paint flowing through the orifices 51 and convey it to the outer ends of the main body of bristles. The manner in which the flexible conduits 48 and 48' are connected to the inner and outer feed blocks forms no part of the present invention. The same has been more fully disclosed and claimed in pending application Serial No. 54,453 filed October 14, 1948.

The inner feed block 46 has an internally-threaded boss 53 formed on the face thereof opposite that through which the outlets leading to the flexible tubing extend. The boss extends into a central passage 54 through the brush so that the main portion of the face from which the boss extends may lie flat against the inner face of the brush head.

A coupling nipple 55 extends through the passage 54 and has its lower end threaded into the boss 53. A nut 55' threaded onto the coupling member or nipple 55 securely holds the coupling member or nipple to the brush head by clamping a portion of the brush head between it and a circumferential flange 60 which extends around the lower end of the coupling nipple and engages the brush head beneath a shoulder 61 of the central passage. The upper end of the coupling nipple bears against a packing ring 56 interposed between it and a seat in the inner end of a coupling member 57 which is threaded into the inner end of a bore or liquid passage 58 extending lengthwise of the handle. The coupling member 57 has a shoulder portion which abuts the handle around the inner end of the lengthwise passage 58 through the handle to provide a space to re-

ceive an inturned end of a coupling nut or sleeve 59 which is threaded onto the outer end portion of the coupling nipple 53. Hence, the threading of the coupling nut onto the outer end of the coupling nipple causes the spaced end portions 44 and 44' of the handle to be pulled towards the brush head and to be firmly clamped against it in the recess 43. The outside of the coupling nut is knurled for better gripping while threading it onto the coupling nipple, and, as shown in Fig. 3, the diameter of the coupling nut is greater than the thickness of the end portion of the handle, so that it may be readily gripped between one's fingers for threading it onto and off of the coupling nipple, as desired.

The recess 43 in the outer face of the brush head has lateral extensions 43^a and 43^b at each end which are of substantially the same shape and size as the spaced end portions 44 and 44', so that when the handle is clamped to the brush head the spaced portions will be received in the extensions 43^a and 43^b and relative rotation between the handle and the head of the brush prevented.

The handle may be made of a single piece of plastic, wood, or light metal such as magnesium or aluminum or one of their alloys, but preferably is made in two pieces, an inner piece 62 of magnesium or aluminum, and an outer piece of wood or plastic.

A lining tube 63 of light metal extends through the fluid passage 58 in the brush handle and has its inner end threaded into an extension 62' on the outer end of the metal handle section 62. The outer end of the metal tube is threaded into a coupling nipple 64 and has the end thereof which extends slightly beyond the outer end of the coupling nipple peened over to prevent removal of the nipple. The coupling nipple 64 has its outer surface threaded to receive a coupling 40 on the end of a length of tubing extending from a reservoir, so that the liquid to be applied may be forced under pressure through such tubing, the handle, the head of the brush and the feed blocks and their connecting flexible conduits to the auxiliary body of bristles 52. The coupling nipple, in addition to forming means for connecting a liquid conducting tube to the handle of the brush, also functions to clamp the outer portion of the handle tightly against the outer end of the metal handle portion 62.

The flow of coating liquid through the handle is controlled by a valve carried by the metal portion 62 of the handle. This valve includes a bushing 65 which is press-fitted into a bore extending transversely through the handle portion 62 and a rotary plug 66. The bushing has openings 67 aligned with the liquid passage which extends lengthwise of the handle, and the rotary plug has an opening 68 which may be brought into and out of alignment with the openings 67. Preferably the opening 68 is slightly elongated in a circumferential direction. The rotary plug 66 has an extension 69 which passes through an end closure disc 70 and is flattened to receive a finger-actuatable lever or handle 71. The side of the valve handle nearest the handle of the brush has an extension 72 which moves in an arcuate groove 73 and limits the movement of the valve handle when it reaches its fully open and its fully closed positions. A packing disc 74 is interposed between the end closure disc 70 and the body portion of the rotary plug.

In each form of the invention described above the handle forms a complete unit of itself so

that it may be manufactured independently of the main portion of the brush and subsequently attached thereto, thereby enabling the handle and brush proper to be obtained from different sources for assembly. Also, as the handle can readily be detached from the remainder of the brush, a worn brush may be removed and a new one attached to the handle, with resulting savings in the cost of a new brush.

The positioning of the cooperating, separable fastening means in the space between the spaced bifurcated portions of the handle between the handle and the brush head gets them out of the way so that they do not interfere with normal use of the brush, yet leaves them in a position which is readily accessible for manipulation.

The interlocking means between the spaced bifurcated inner portions of the handle ensures that when the handle is attached to the brush head no relative movement will take place between them which would interfere with normal use of the brush.

We claim:

1. A handle for a brush having the end thereof which is to be connected to the brush bifurcated to provide spaced portions, the distal ends of which are constructed and arranged to bear firmly against the head of the brush, and a part of cooperating, separable connecting means for firmly holding the distal ends of the spaced portions against a brush head carried by the handle and positioned in the space between said spaced portions, said part of the cooperating, separable connecting means being adapted to cooperate with a supplemental portion of the separable connecting means carried by the brush head to fixedly and immovably connect the distal ends of the spaced portions of the handle to the brush head.

2. A handle for a brush having the end thereof which is to be connected to the brush bifurcated to provide spaced portions, the distal ends of which are constructed and arranged to bear firmly against the head of the brush, and a part of cooperating, separable connecting means for firmly holding the distal ends of the spaced portions against a brush head carried by the handle and positioned in the space between said spaced portions, said part of the cooperating, separable connecting means being adapted to cooperate with a supplemental portion of the separable connecting means carried by the brush head to fixedly and immovably connect the distal ends of the spaced portions of the handle to the brush head, the distal ends of said spaced portions of the handle having parts engageable with the brush head to interlock therewith and prevent relative rotation of the handle and brush head about the longitudinal axis of the handle.

3. A handle for a fountain, liquid-applying brush having the end thereof which is to be connected to the brush bifurcated to provide spaced portions, the distal ends of which are constructed and arranged to bear firmly against the head of the brush, and a part of cooperating, separable connecting means for firmly holding the distal ends of the spaced portions against a brush head carried by the handle and positioned in the space between said spaced portions of the handle, said part of the cooperating, separable connecting means being adapted to cooperate with a supplemental portion of the separable connecting means carried by the brush head to fixedly and immovably connect the distal ends of the spaced portions of the handle to the brush head, said part of the cooperating, separable connecting means carried

by the handle having a passage therethrough for the flow of liquid to the head of the brush.

4. A handle for a fountain, liquid-applying brush having a liquid passage extending lengthwise therethrough, said handle also having the end thereof which is to be connected to the brush bifurcated to provide spaced portions, the distal ends of which are constructed and arranged to bear firmly against the head of the brush, and a part of cooperating, separable connecting means for firmly holding the distal ends of the spaced portions against a brush head carried by the handle and positioned in the space between said spaced portions of the handle, said part of the cooperating, separable connecting means being adapted to cooperate with a supplemental portion of the separable connecting means carried by the brush head to fixedly and immovably connect the distal ends of the spaced portions of the handle to the brush head, said part of the cooperating, separable connecting means carried by the handle having a passage therethrough communicating with the liquid passage in the handle so that liquid may be supplied through the handle and the part of the cooperating, separable connecting means carried thereby to the head of a fountain, liquid-applying brush.

5. A handle for a fountain, liquid-applying brush having a liquid passage extending lengthwise therethrough, said handle also having the end thereof which is to be connected to the brush bifurcated to provide spaced portions, the distal ends of which are constructed and arranged to bear firmly against the head of the brush, and a part of cooperating, separable connecting means for firmly holding the distal ends of the spaced portions against a brush head carried by the handle and positioned in the space between said spaced portions of the handle, said part of the cooperating, separable connecting means being adapted to cooperate with a supplemental portion of the separable connecting means carried by the brush head to fixedly and immovably connect the distal ends of the spaced portions of the handle to the brush head, said part of the cooperating, separable connecting means carried by the handle having a passage therethrough communicating with the liquid passage in the handle so that liquid may be supplied through the handle and the part of the cooperating, separable connecting means carried thereby to the head of a fountain, liquid-applying brush, and a valve for controlling the flow of liquid through the passage in the handle.

6. A handle for a brush having the end thereof which is to be connected to a brush bifurcated to provide spaced portions, the distal ends of which are constructed and arranged to bear firmly against the head of a brush, a coupling member carried by the handle in the space between said spaced portions, and a coupling nut rotatively mounted on said coupling member and adapted to engage a threaded portion carried by the head of a brush for connecting the handle to such a brush head.

7. A handle for a brush having the end thereof which is to be connected to a brush bifurcated to provide spaced portions, the distal ends of which are constructed and arranged to bear firmly against the head of a brush, a coupling member carried by the handle in the space between said spaced portions, a coupling nut rotatively mounted on said coupling member and adapted to engage a threaded portion carried by the head of a brush and connecting the handle to

such a brush head, and interengaging parts carried by the coupling member and the coupling nut effective on screwing the coupling nut onto a threaded portion carried by the brush head to bring the distal end portions of the bifurcated portion of the handle into firm engagement with the brush head.

8. In a brush, the combination of a brush head having bristles mounted at one end thereon, and 10 extending therefrom in a generally parallel group, a handle having one end bifurcated to provide spaced portions, the distal ends of which engage the brush head, and cooperating, separable connecting means carried, respectively, by the handle and the brush head, said cooperating separable connecting means being positioned between said spaced portions of the handle, between the handle and the brush head, and detachably connecting the handle to the brush head and holding the distal ends of the bifurcated portions in fixed and immovable engagement with the brush head.

9. In a brush, the combination of a brush head having bristles mounted at one end thereon, and 25 extending therefrom in a generally parallel group, a handle having one end bifurcated to provide spaced portions, the distal ends of which engage the brush head, and cooperating, separable connecting means carried, respectively, by the handle and the brush head, said cooperating separable connecting means being positioned between said spaced portions of the handle, between the handle and the brush head, and detachably connecting the handle to the brush head and holding the distal ends of the bifurcated portions in firm engagement with the brush head, said spaced portions of the handle and the brush head having interlocking portions which prevent relative rotation of the handle and the brush head about an 35 axis extending lengthwise of the handle.

10. In a fountain, liquid-applying brush, the combination of a brush head having a passage through which liquid may flow, a body of bristles mounted at one end on the brush head, and 45 extending therefrom in a generally parallel group, the brush head also having a passage for conducting liquid from said first-mentioned passage to said body of bristles, a handle having a liquid passage extending lengthwise thereof, said handle having its inner end bifurcated to provide spaced portions, the distal ends of which engage the brush head, and cooperating, separable connecting means carried, respectively, by the handle and the brush head and positioned between said 55 spaced portions of the handle, between the handle and the brush head, detachably connecting the handle to the brush head and holding the distal ends of the bifurcated portions in fixed and immovable engagement with the brush head, the 60 cooperating, separable connecting means having communicating passages extending through them and communicating, respectively, with the passage in the handle and the first-mentioned passage in the brush head, whereby liquid flowing 65 through the handle may flow through said cooperating, separable connecting means to the passages in the brush head and to the body of bristles.

11. In a fountain, liquid-applying brush, the 70 combination of a brush head having a passage through which liquid may flow, a body of bristles mounted at one end on the brush head, and extending therefrom in a generally parallel group, the brush head also having a passage for conducting liquid from said first-mentioned passage

to said body of bristles, a handle having a liquid passage extending lengthwise thereof, said handle having its inner end bifurcated to provide spaced portions, the distal ends of which engage the brush head, cooperating, separable connecting means carried, respectively, by the handle and the brush head and positioned between said spaced portions of the handle, between the handle and the brush head, detachably connecting the handle to the brush head and holding the distal ends of the bifurcated portions in fixed and immovable engagement with the brush head, the cooperating, separable connecting means having communicating passages extending through them and communicating, respectively, with the passage in the handle and the first-mentioned passage in the brush head, whereby liquid flowing through the handle may flow through said cooperating, separable connecting means to the passages in the brush head and to the body of bristles, and a valve for controlling the flow of liquid through the passage in the valve handle.

12. In a brush, the combination of a brush head having bristles mounted at one end thereon and extending therefrom in a generally parallel group, a handle having one end bifurcated to provide spaced portions, the distal ends of which engage the brush head, a coupling member carried by the handle in the space between said spaced portions, and a coupling nut rotatively mounted on said coupling member and threadedly connected to a threaded portion carried by the head of the brush for connecting the handle to the brush head and holding the distal ends of the bifurcated portions in firm engagement with the brush head.

13. In a brush, the combination of a brush head having bristles mounted at one end thereon and extending therefrom in a generally parallel group, a handle having one end bifurcated to provide spaced portions, the distal ends of which engage the brush head, a coupling member carried by the handle in the space between said spaced portions, and a coupling nut rotatively mounted on said coupling member and threadedly connected to a coupling nipple carried by the head of the brush for connecting the handle to the brush head and holding the distal ends of the bifurcated portions in firm engagement with the brush head.

14. In a fountain, liquid-applying brush, the combination of a brush head having a passage through which liquid may flow, a body of bristles mounted at one end on the brush head and extending therefrom in a generally parallel group, the brush head also having a passage for conducting liquid from said first-mentioned pas-

5 10 15

sage to said body of bristles, a handle having a liquid passage extending lengthwise thereof, the inner end of said handle being bifurcated to provide spaced portions, the distal ends of which engage the brush head, a coupling member carried by the handle in the space between said spaced portions, and a coupling nut rotatively mounted on said coupling member and engaging a threaded portion carried by the head of the brush for connecting the handle to the brush head and holding the distal ends of the bifurcated portions in firm engagement with the brush head, said coupling member and the threaded portion carried by the brush head having passages through them which connect, respectively, with the liquid passage in the brush handle and the liquid passages in the brush head.

15. In a fountain, liquid-applying brush, the combination of a brush head having a passage through which liquid may flow, a body of bristles mounted at one end on the brush head and extending therefrom in a generally parallel group, the brush head also having a passage for conducting liquid from said first-mentioned passage to said body of bristles, a handle having a liquid passage extending lengthwise thereof, the inner end of said handle being bifurcated to provide spaced portions, the distal ends of which engage the brush head, a coupling member carried by the handle in the space between said spaced portions, a coupling nut rotatively mounted on said coupling member and engaging a threaded portion carried by the head of the brush for connecting the handle to the brush head and holding the distal ends of the bifurcated portions in firm engagement with the brush head, said coupling member and the threaded portion carried by the brush head having passages through them which connect, respectively, with the liquid passage in the brush handle and the liquid passages in the brush head, and a valve for controlling the flow of liquid through the passage in the handle.
